CLAIM

The ornamental design for a solar carport and charging system as shown and described.

DESCRIPTION

FIG. 1 is a left front perspective view showing the ornamental design of the claimed solar carport and charging system;

FIG. 2 is a front view thereof;

FIG. 3 is a back view thereof;

FIG. 4 is a left side view thereof;

FIG. 5 is a right side view thereof; and,

FIG. 6 is a top view thereof.

The bottom side is not part of the claimed design.

In FIGS. 3, 4 and 5 the dash-dash broken lines are for the purpose of illustrating portions of the solar carport and charging system that form no part of the claimed design.

1 Claim, 6 Drawing Sheets
